VACUUM NURSING BOTTLE WITH JACKET

Claude Thompson Jamison and Vernon Philip
Brewer, Alton, Ill.

Application October 31, 1946, Serial No. 706,832

1 Claim. (Cl. 215—11)

1

This invention relates to nursing bottles and nipples.

An object of this invention is to provide an improved nursing bottle construction which includes in combination a vacuum container and a nipple secured to the container.

Another object of this invention is to provide an improved vacuum container and means for cushioning the container in its casing so that the container will not be broken if the casing and container are dropped.

A further object of this invention is to provide in combination a vacuum container in a casing, a nipple secured to the container, and means whereby the nipple may be sealed to prevent leakage so that the contents will not leak out of the container if the latter is laid on its side.

A further object of this invention is to provide a nursing bottle construction wherein the contents may be kept warm for a relatively long period so that a night feeding of the baby may be accomplished easily and quickly and at a minimum of inconvenience.

With the above and other objects in view, our invention consists in the arrangement, combination and details of construction disclosed in the drawing and specification, and then more particularly pointed out in the appended claim.

In the drawing,

Figure 1 is a vertical section, partly broken away and in elevation, of a nursing bottle construction embodying this invention,

Figure 2 is an enlarged view, partly in section and partly in elevation, of the upper portion of the assembly,

Figure 3 is a plan view of the device with the outer cap removed.

Referring to the drawing, the numeral 10 designates generally a vacuum bottle of conventional construction which is formed with a neck 11. The bottle 10 is mounted in an outer casing generally designated as 12, which includes a cylindrical side wall 13 and a bottom wall 14. The side wall 13, at spaced points therealong, is formed with outwardly offset ribs 15 within which are seated cushioning rings 16 formed of rubber or other resilient material, which are adapted to engage about the bottle 10 so as to cushion the bottle 10 within the container 12 and thereby prevent breakage of the bottle when the container is dropped or the like.

A rubber bottom cushioning member 17 formed with a concave upper end 18 is disposed on the inside of the casing bottom 14 and cushions the bottle 10 against endwise movement. The casing

2

12 has threaded into the upper end thereof a bottle retaining cap generally designated as 19. The cap 19 is formed with a threaded lower portion 20 engaging complementary threads 21 carried by the upper end of the casing 12 and the upper end of the cap or retaining member 19 is formed with an inturned annular flange 22 extending over the upper end of the bottle 10. A rubber sealing ring 23 is interposed between the flange 22 and the upper end of the bottle 10 so as to cushion the bottle relative to the retaining member 19.

The bottle 10 is adapted to have removably mounted in the upper end thereof, a nipple generally designated as 24. The nipple 24 includes a stopper lower body 25 which is adapted to engage in the neck 11 of the bottle. The stopper body 25 is formed with an annular flange 26 adapted to bear against the outer side of the retaining flange 22. The stopper body 25 has extending from the upper end thereof a nipple body 27 which is of substantially conventional construction, being formed with openings 28 whereby the liquid in the bottle 10 may be drawn therefrom. The nipple 24 is adapted to be firmly secured to the upper end of the bottle 10 by means of a cap 29 which is formed with a threaded annulus 30 threadably engaging threads 31 formed on the upper end of the retaining member 19.

In order to provide a means whereby the nipple may be sealed when not in use so as to prevent leakage of the contents thereof, we have provided an outer cap 32 which is threaded as at 33 on threads 34 formed on the retaining member 19 outwardly of the lower threads 20. The cap 32 includes a cylindrical side wall 35 and an outer or top wall 36 and the side wall 35 is of such length that when the cap 32 is threaded on the threads 34, the top wall 36 will bend the nipple 27, as shown in Figure 1, forming a bend 37 between the ends of the nipple 27 and thereby forming a seal so that the liquid will not leak out of the nipple openings 28.

In the use of this nursing bottle, the liquid contents are inserted through the neck 11, the nipple 24 being removed by unthreading the cap 29. The contents are pre-heated to the desired degree before being placed in the vacuum bottle 10 so that when the nipple 24 is secured by the cap 29 on the bottle, the contents will remain in the heated condition for a relatively long period of time. The bottle construction hereinbefore described has been designed particularly for night feeding and after the nipple 24 has been secured to the filled bottle, the cap 32 is threaded on the retaining cap

19 so that the nipple 24 will be bent as at 37 to seal the nipple against leakage of the contents of the bottle 10.

This vacuum bottle construction will make it unnecessary to heat the milk or formula during the night so that the baby can readily be fed by merely removing the cap 32. In the event the bottle is dropped, the inner container or vacuum bottle 10 will not be broken due to the cushioned mounting of the inner container relative to the 10 outer casing 12.

We do not mean to confine ourselves to the exact details of construction herein disclosed, but claim all variations falling within the purview of the appended claim.

What we claim is:

A nursing bottle construction comprising a vacuum bottle, a casing for said bottle having a threaded upper portion, a bottle retaining cap for holding said bottle in said casing, including a threaded skirt for engaging said portion and an inwardly directed flange adapted to overlie the top of said bottle, a nipple having a stopper portion engageable within the neck of said bottle and

5 an outwardly directed flange adapted to seat on top of said cap flange, an annular nipple securing member threadedly carried by the top of said cap and adapted to clamp said nipple flange between said member and said cap flange whereby said nipple may be removed from said bottle when said securing member is disengaged from said bottle retaining cap, and an outer cap engageable over the top portion of said skirt.
